LUCIE ARVILLA GRAHAM, OF NEW YORK, N. Y.

DESIGN FOR A SKIRT AND WAIST SUPPORTER.

SPECIFICATION forming part of Design No. 31,386, dated August 8, 1899.

Application filed July 13, 1899. Serial No. 723,739. Term of patent 7 years.

To all whom it may concern:

Be it known that I, LUCIE ARVILLA GRAHAM, a citizen of the United States, residing at New York, in the county of New York, State 5 of New York, have invented a certain new and original Design for Skirt-Supporters, of which the following is a description, reference being had to the accompanying drawing and to the letters of reference marked thereon.

10 My invention relates to a new and original design for skirt and waist supporters; and the leading feature consists in a skirt and waist supporter of the shape and configuration hereinafter described, and illustrated in the accompanying drawing, in which the figure is a 15 front elevation of a skirt and waist supporter embodying my design.

In the drawing, A represents a bar or plate provided with the longitudinal tapering openings a, the central solid body portion b, the round openings c at the ends, and the down-

wardly-extending arms d. Projecting upwardly from about the central point of the bar A is an arm e, which extends upwardly and then is bent over and downwardly, forming the widened portion f, this portion f being convexed, said enlarged part f having upon it the ornamentation shown in the drawing. 25

The leading feature consists of the bar or plate having the upwardly and downwardly 30 extending hook portion e, having the floured ornamentation on the enlarged part f.

I claim—

15 The design for a skirt and waist supporter; substantially as shown and described. 35

In testimony whereof I affix my signature in presence of two witnesses.

LUCIE ARVILLA GRAHAM.
